TEMPLATE

Ralph C. Grace, San Francisco, Calif.

Application September 8, 1937, Serial No. 162,897

14 Claims. (Cl. 33—185)

The present invention relates to improvements in templates and has particular reference to a template intended for use in connection with a sticker machine, although it may be used for other purposes.

A sticker machine is used in the wood-working industry for making mouldings, the general idea of the sticker machine being to advance a strip or "stick" of wood to pass over a revolvable cutter which latter cuts the desired shape into one face of the stick. The cutter blade is mounted on a revolvable cutter head which in the standard machines is square in cross-section to present four rectangular faces and an equal number of corners, the blades being secured to the faces so as to project beyond the corners.

The positioning of these blades so as to obtain a desired result is difficult because there is no possible way of ascertaining the desired radial distance of the cutting edge from the axis of rotation.

The only dimension that can be conveniently established is the depth to which the blade projects beyond the corner of the cutter head. But since the blade does not project in radial direction, the depth of the projecting blade does not correspond to the depth of cut desired. If, for instance, it is desired to cut into the stick to the depth of one half an inch from a base line and the blade is made to project from a corresponding line on the cutter head by the same distance of one half inch, the blade would cut into the stick to a depth somewhat less than one half an inch and it is necessary to raise the blade somewhat higher than one half inch to produce a one half inch cut. This difference is referred to in the trade as the "gain" and is difficult to establish and the correct positioning of the blade on the cutter head causes many expensive delays.

It is the object of the present invention to provide a template which allows the gain or rather the total depth of projection of the blade beyond the corner of the cutter head to be established quickly, without any difficulty and without the display of any particular skill on the part of the operator.

Further objects and advantages of my invention will appear as the specification proceeds.

The preferred form of my invention is illustrated in the accompanying drawings, in which

Figure 1 shows a front view of my template with the outline of a moulding in end view marked thereon in heavy lines;

Figure 2 a similar view showing the template

expanded, with a corresponding change in form of the outline of the moulding;

Figure 3 a front view showing the left-hand side in expanded position, the right-hand side in normal position, certain end portions being omitted to show interior construction;

Figure 4 a section taken along line 4—4 of Figure 3;

Figure 5 a perspective detailed view of parts entering into the end assemblies of my template;

Figure 6 a perspective detailed view showing two fragmentary bars in their co-operative relationship;

Figure 7 a section taken along line 7—7 of Figure 3;

Figure 8 a rear view of the template;

Figure 9 an end view of a cutter head with co-related parts explaining the use of the template, and

Figure 10 a diagrammatic view explaining the theory of the template.

While I have shown only the preferred form of my invention I wish to have it understood that various changes or modifications may be made within the scope of the claims hereto attached without departing from the spirit of the invention.

Referring to the drawings in detail, attention is first called to Figure 9 which shows a cutter head 1 mounted on the revolvable shaft 2, the cutter head being square in end view so as to present four faces and four corners joining the faces.

A blade 3 is shown attached to each face by any suitable means as by the bolt 4, with a portion 5 projecting beyond the corner. The latter portion has a cutting edge 6 which may be suitably shaped to conform to the outline of molding desired. The cutter head rotates in the direction of the arrow.

The cutter head is mounted under a table or guide 7 over which a stick 8 is advanced in the direction of the arrow, the table or guide having an opening 9 permitting the cutters to cut into the underface of the advancing stick. This machine is known as a sticker machine and the depth of cut depends upon the distance which the cutter blade projects beyond the adjacent corner of the cutter head.

The most convenient way of adjusting the blade to the desired height is by means of a gauge or template 10 such as indicated in dotted lines in Figure 9 which uses the adjacent face of the cutter head as a base. But since the blade occupies an angular position instead of a radial

position, the desired measurements cannot be applied without being first modified and corrected, as will be easily seen by reference to Figure 10, which diagrammatically illustrates the principle on an enlarged scale.

The cutting action takes place at the vertical centerline indicated at 11 while the blade is shown at 3. If it is desired to cut into the stick to the depth of one-eighth of an inch as outlined 10 on the vertical center line, the blade must be raised by a distance somewhat more than one-eighth of an inch as defined between the two circles and marked one-eighth of an inch plus gain. This gain varies with the size of the circle, the 15 gain getting less the larger the circle grows.

It is proposed in the present invention to construct the template 10 in such a manner that, if applied as in Figure 9, it will permit the blade to be adjusted so as to automatically take care 20 of the gain and to compensate for the same.

My template comprises in its principal features a rectangular frame 12, a plurality of bars 13 movable in the frame and means associated with the ends of the frame for adjusting the bars.

25 The frame 12 is made in two parts, a rear section 14 and a front section 15, the two sections being similar in shape and being secured to one another to form a support for the operating mechanism. The section 14 comprises an upper member 16, a lower member 17 and end members 18 and is strengthened by three vertical braces 19, two of which are formed with elongated vertical slots 20, (see Figure 8).

The section 14 is made of two substantially 35 identical parts which are fastened upon one another by means of screws 21 and which form elongated cavities 22 in the lower frame member 17 adapted to slidably receive rods 24 forming hooks 25 at the ends thereof.

40 These hooks 25 may be placed against the end of the cutter head, as shown in Figure 9, to insure a proper position of the template on the face of the cutter head. They are adjustable, as is apparent by their construction and may be fixed in adjusted position by means of screws 26 threaded into the sleeves 23 through slots 27 and bearing on the rods 24. When not in use the hook may be retracted and made to disappear in the recess 28 as shown on the right hand side of 50 Figure 8. The rear section 14 has a forwardly projecting flange 29 along the bottom edge thereof.

The front section 15 is somewhat similar to the rear section and comprises an upper member 30, 55 a bottom member 31 and end members 32. It also has vertical braces 33 which register with the two outer braces 19 of the rear section 14 and may be secured thereto by means of sockets 34 projecting from the rear faces of the braces 33 into the slots 20 of the braces 19 and clamped to the latter braces by screws 35 threaded into the sockets. The slots allow the front section to be adjusted 60 relative to the rear section.

When the front section is secured to the rear 65 section, the front face of the front section is on a plane with the front face of the flange 29 projecting from the rear section, as clearly appears from Figure 7, and the end members 32 of the front section are flush with the end members 18 of the rear section on the outside, as shown in Figure 4, but are much narrower so as to form pockets 36 therewith, which are bridged by thin end plates 37 secured to the top and bottom members 30 and 31 of the front section by means of 70 screws 38. The top and bottom members 30 and 75

31 are slightly depressed to receive the end plates so that the faces of the latter are flush with the front face of the front section of the frame.

Upon the frame are mounted, with freedom of vertical sliding motion, a plurality of bars 13 5 which extend horizontally across the frame, their front faces flush with the front faces of the front section and the flange 29, and their ends being slightly recessed, as at 41, to fit underneath the end plates 37. The bars are grooved, 10 as at 42, over the braces 33, which themselves are slightly set back to serve as vertical guides for the bars without pressing the same out of the front plane. The grooves are sufficiently wide to allow of a small amount of play of the bars on 15 the braces. The bars are all of the same width and for the purposes of my invention I find that a width of one-eighth of an inch gives satisfactory results. Each bar terminates, at the ends, in a tooth 43.

The height of the frame is such, relative to the width and number of the bars, that when the bars are arranged in adjacent relation, as in Figure 1, a considerable space is left above the bars so that the same may be spread or separated as in Figure 2. For spreading the bars I provide, opposite the toothed ends in each side pocket, a toothed spreader or spacer 44, which has a number of teeth 45 adapted for engagement with the teeth of the bars, but spaced in such a manner that when all the teeth are engaged the bars are spaced from one another as shown in Figure 2. It should be observed that springs 46 (see Figures 6 and 2) are interposed between the bars and tend to separate them.

The spreader is movable sidewise in the pocket at each end of the template for engagement with and disengagement from the teeth at the ends of the bars. The position of engagement is shown at the left end of Figure 3 and the position of disengagement at the right end. The spreader is operated by the actuating plate 47 (see Figure 5) which overlies the spreader plate and is shown in dotted line positions in Figure 3. This plate is also accommodated in the pocket at each end with freedom of vertical sliding movement and is guided vertically by the end member 32 of the front frame section which projects into a groove 48 formed between a rib 49 and the projecting finger piece 50.

The actuating plate has two prongs 51 and 52 projecting from its bottom face and these prongs enter into registering slots 53 and 54 of the spreader plate 44. Both of these slots are curved but it will be noted that the curve in slot 53 begins at a lower point than that in slot 54 so that, when the actuating plate is pushed upward the spreader plate moves into engagement with the bars progressively, beginning at the bottom and proceeding upwardly from tooth to tooth, as the bars spread under the influence of their respective springs 46.

The actuating plate 47 has a tongue 55 projecting from its upper edge so as to overlie the uppermost bar and to compress the bars into adjacent relation against the resistance of the springs 46 when the actuating plate is moved downward.

The plate 47 has two spaced depressions 56 adapted for engagement by a projection 57 in the 70 cover plate 31 for yieldingly holding the actuating plate in either of its end positions.

The bars are suitably graduated into inches and one-eighth inches to conform to a standard ruler.

My template is used as follows:

Assuming it is desired to cut a moulding of the cross-section shown in heavy outline on the template shown in Figure 1. The first step is to 5 adjust the front and rear sections of the template relative to one another so as to establish a suitable base line in the bottom line of the bottom member 31 of the front section, which should be adjusted so that a blade set to the 10 height of the base line, when the template is used as in Figure 9 should just contact, with a slight shaving action, the bottom of the stick passing through the machine. The adjustment need never be changed as long as the template is used 15 for the same machine or type of machine.

Next a small piece of molding of the desired type is taken, its end placed against the front face of the template and its outline traced, by pencil or other tool, over the base line, as shown 20 in Figure 1.

It will be understood that a plurality of blades are conventionally used to cut into a stick or moulding at different places to produce the continuous curve or other shape desired. Assuming 25 that four blades are used as shown in Figure 9, it is necessary, of course, to arrange the four blades in staggered relation longitudinally on the cutter head so that each blade is in the proper place for doing its particular share of the work. 30 This longitudinal adjustment is taken care of by adjustment of the blades on the cutter head or of the fingers 25 in such a manner that when the template is placed on the cutter head with the finger 25 hooked over one end of the cutter 35 head, as in Figure 9, each blade occupies its proper position relative to the stick to be cut and to the outline of the moulding on the template.

Now the actuating members 41 are operated on 40 each end of the template by pushing the same upward. The first effect of this movement is that the bars are released from the hold of the fingers 55 and allowed to spread under the influence of the springs 46. But the upward movement of each actuating member also pushes the spreader 45 plate 44 toward the bars, first at the bottom and then at the top so that the teeth of the spreader progressively engage with the teeth of the bars, as the latter spread under the influence of their 50 springs and when the engagement is completed the bars are firmly held by the spreader members in the spaced relation shown in Figure 2.

The teeth on the spreader plate 44 are spaced so that the spacing between the bars in final 55 position exactly corresponds to the "gain" to be added for the width of each bar to produce the correct height for each blade when the template is applied as in Figure 9.

To produce the correct adjustment of each 60 blade it is now only necessary to place the template behind each blade as shown in Figure 9 and to raise each blade to the distorted outline of the moulding behind the blade.

Referring now to Figures 8 and 9, it will be 65 noted that in the event the shaft 2 should be slightly out of parallel with the top of the table 7, the rear section 14 of the frame 12 may be twisted relative to the front section 15. The slots 20 will permit this angular adjustment, and the 70 bottom of the lower member 17 may be presented parallel to the shaft 2, while the bars 13 will be parallel with the table top.

In making the lower surface cut as indicated by the numeral 32 in Figure 1, the template may 75 be turned upside down from the dotted line posi-

tion shown in Figure 9. The blade for this particular cut is then adjusted until it strikes the edge 16' of the upper member 16 (see Fig. 7). It will be noted in this connection that the distance from the edge 16' to the top 30' of the member 30 is always the same as the distance 5 from the bottom 29' of the flange 29 to the lower edge 31' of the bottom member 31 (see Fig. 7).

I claim:

1. A template of the character described comprising a rectangular frame having a top member, a bottom member and end members, a plurality of bars having their ends slidable in the end members, and means associated with each end member for adjusting the spacing between 10 the adjacent ends of the bars in a single operation.

2. A template of the character described comprising a frame, a plurality of bars movable in the frame, actuating members movable longitudinally in the frame and having means for urging the bars into engaging relation when moved in one direction and releasing the bars for spacing when moved in the other direction, toothed members slidable transversely and adapted for 20 engagement with the bars for controlling the spacing between the bars, and means on the actuating members for operating the toothed members while the bars are released for spacing, the latter means being made to effect a progressive engagement of the toothed members 25 with the bars from one end of the toothed members to the other.

3. A template of the character described comprising a frame, a plurality of solid-faced parallel bars movable in the frame, each bar having an unobstructed face, and means operable on the bars for moving the latter between positions of engaging relation, in which the bars present a continuous and solid surface, and positions of 30 predetermined differential spacing between the bars, said means being made to space the bars apart with the spaces between adjacent bars progressively increasing from one side of the frame 35 to the other side thereof when the bars are spaced apart.

4. A template of the character described comprising a frame, a plurality of solid-faced parallel bars movable in the frame, each bar having an unobstructed face, and means at each 50 end of the frame operable on the bars for moving the latter between positions of engaging relation, in which the bars present a continuous and solid surface, and positions of predetermined spacing between the bars, said means being made 55 to space the bars apart with the space between adjacent bars progressively increasing from one side of the frame to the other side thereof when the bars are spaced apart.

5. A template of the character described comprising a frame, a plurality of bars movable in the frame, actuating members slidable in the ends of the frame and having means for moving the bars into engaging relation with each other to present a continuous and solid surface when 60 the actuating members are moved in one direction, and means operated by the actuating members and engageable with the bars for effecting a predetermined differential spacing between the bars when the actuating members are moved in 65 the opposite direction.

6. A template of the character described comprising a frame, a plurality of bars movable in the frame, spring means interposed between adjacent bars for urging the latter apart, actuati- 70 75

ing members slidable in the ends of the frame and having means for moving the bars into engaging relation with each other to present a continuous and solid surface when the actuating members are moved in one direction and means operated by the actuating members and engageable with the bars for effecting a predetermined differential spacing between the bars when the actuating members are moved in the opposite direction.

7. A template of the character described comprising a frame, a plurality of bars movable in the frame, spring means interposed between adjacent bars for urging the latter apart, actuating members movable longitudinally in the ends of the frame and having means for moving the bars into engaging relation with each other to present a continuous and solid surface when the actuating members are moved in one direction and releasing the bars for spacing when the actuating members are moved in the opposite direction, toothed members slidable transversely in the ends of the frame and adapted for engagement with the ends of the bars for controlling the spacing between the bars, and means on the actuating members for operating the toothed members while the bars are released for spacing.

8. A template of the character described comprising a frame, a plurality of bars movable in the frame, spring means interposed between adjacent bars for urging the latter apart, actuating members movable longitudinally in the ends of the frame and having means for moving the bars into engaging relation with each other to present a continuous and solid surface when the actuating members are moved in one direction and releasing the bars for spacing when the actuating members are moved in the opposite direction, toothed members slidable transversely in the ends of the frame and adaptable for engagement with the ends of the bars for controlling the spacing between the bars, and means on the actuating members for operating the toothed members while the bars are released for spacing, the latter means being made to effect a progressive engagement of the toothed members with the bars from one end of the toothed members to the other.

9. A template of the character described comprising a rectangular frame having a top member, a bottom member and end members, a plurality of bars having their ends slidable in the end members, and means movable relative to the frame and engaging with the bars for adjusting the spacing between the bars.

10. In a template, a plurality of bars, means for moving the bars into engaging relation with each other to form a solid face, means operable on the bars for urging the bars apart, means for releasing the bars for movement into separated relation, and means engageable with the bars

for controlling the separating movement and effecting a predetermined differential spacing between the bars.

11. In a template, a plurality of bars, means for moving the bars into engaging relation with each other to form a solid face, means operable on the bars for urging the bars apart, means for releasing the bars for movement into separated relation, and means engageable with the bars for controlling the separating movement and effecting a predetermined differential spacing between the bars, the latter means being made to progressively engage successive bars from one side of the template to the other.

12. A template of the character described comprising a frame, a plurality of solid-faced bars movable in the frame, actuating members movable longitudinally in the ends of the frame and having means operable on the bars for moving the latter into engaging relation with each other to present a continuous and solid surface when the actuating members are moved in one direction and for releasing the bars when the actuating members are moved in the opposite direction, toothed members slidable transversely in the frame and adapted for engagement with the bars for controlling the spacing of the bars, and means on the actuating members for operating the toothed members while the bars are released for spacing.

13. A template of the character described comprising a frame having front and rear frame sections arranged face to face, means for adjusting the sections for extending one section relative to the other, the rear section forming a base, a plurality of bars movable in the front section, actuating members operable on the bars for moving the latter into engaging relation with each other to present a solid surface when the actuating members are moved in one direction, and means operated by the actuating members for effecting a predetermined differential spacing between adjacent bars when the actuating members are moved in the opposite direction.

14. A template of the character described comprising a frame having front and rear frame sections arranged face to face, means for adjusting the sections for extending one section relative to the other and for moving the frame sections into angular relation with respect to each other, the rear section forming a base, a plurality of bars movable in the front section, actuating members operable on the base for moving the latter into engaging relation with each other to present a solid surface when the actuating members are moved in one direction, and means operated by the actuating members for effecting a predetermined differential spacing between adjacent bars when the actuating means are moved in the opposite direction.

RALPH C. GRACE.
